(Cl. D59—2)

FIG. 1

FIG. 2

FIGURE 1 is a front perspective view of a data record card or similar article embodying my new design.

FIGURE 2 is a rear perspective view of the same.

The characteristic feature of my design resides in the combination on a data card of the type disclosed of the paired arrangement of slanted teeth, comprising a narrow tooth and a wide tooth separated by rounded notches substantially as shown.

I claim:

The ornamental design for a data record card or similar article, substantially as shown and described.
